UNITED STATES PATENT OFFICE

2,620,756

DISPENSER TUBE FOR CONFECTIONERY ON
CAKES AND CANDIES

Charles A. Krens, Staten Island, N. Y.

Application April 14, 1949, Serial No. 87,393

6 Claims. (Cl. 107—52)

1

This invention relates to new and useful improvements in devices for applying frosting or coatings to candies, cakes, and the like.

A main object of the invention is to provide a simple, efficient, economical, easily operated device for applying simultaneously a plurality of different coatings in one operation.

A further object is to provide a simple construction of a bag and multiple spout whereby a plurality of different confection coatings may be contained and dispensed in one operation.

A still further object is to provide a device which can be quickly and easily assembled and disassembled for inspection, replacement and repair.

Further and more specific objects, features, and advantages will more clearly appear from a consideration of the detailed specification hereinafter set forth especially when taken in connection with the accompanying drawings which illustrate a present preferred form which the invention may assume and which form part of the specification.

In brief and general terms, the invention concerns connecting a plurality of bag compartments at their lower ends separately to spout sections which may be held together, but provide independent passages for material therethrough, so that a plurality of different materials may be separately or simultaneously dispensed through a common nozzle.

The invention may also comprise a single bag divided into a plurality of compartments and connected at its lower end to a spout construction including spout sections connected separately to the several bag compartments. The spout sections have flat, adjacent, abutting surfaces adapted to be interlocked and the upper portions of which are spaced somewhat apart with interlocking ridges and grooves to receive therebetween the partition or partitions of the bag. The various sections of the spout when thus assembled, form a complete unitary spout member and the sections are held together by screw collars; the shape of the spout sections when assembled being tapered. A nozzle of any suitable proportion and having an opening of predetermined shape, is clamped on to the end of the spout by means of a screw collar. A blade extends downwardly from one of the spout sections and well into the nozzle portion to keep the confectionery material issuing from the various sections, separate until just before they issue from the end of the nozzle.

The preferred present form which the inven-

2

tion may assume is illustrated in the drawings, of which:

Fig. 1 is a side elevation of the entire dispensing unit;

Fig. 2 is an enlarged vertical section of the lower portion thereof;

Fig. 3 is a horizontal section taken on the line 3—3 of Fig. 2; and,

Figs. 4 and 5 are respective perspective views of the spout sections which are two in number in this form, and are adapted to be connected to two separate compartments in the dispensing bags.

Referring now merely to the specific form of the invention shown in the drawings, it will be seen that I have provided the usual confectioner's bag 10, provided with a central partition 11 sewed thereto and extending well down towards the bottom thereof and dividing the bag, into two compartments. Snugly disposed in the bottom of the respective compartments of the bag 10, are spout sections 12 and 13 of semi-circular cross section and of downwardly tapered configuration as shown. These sections are provided with flat lower adjacent surfaces, one of which is provided

with an elongated opening 15 to receive a similarly shaped projection or tongue 16 on the corresponding portion of the face of the other section.

When these two sections are placed together, the tongue 16 lies in the hole 15 and the two sections when thus abutting, form a complete tapered spout forming two discharge passages connected respectively to the compartments of the bag. As will be seen in Figure 2, these sections fit snugly into the bottom of the bag. The outer periphery of these spout sections is provided with a series of upper screw threads 17 and a series of lower threads 18 separated by an intermediate smooth, ring-like surface 19, and a similar surface 20 is disposed below the series of threads 18. The upper adjacent face sections 21 of the spout sections are offset so as to be spaced apart as shown in Figure 2, when the two sections are placed together. In this passage thus formed, is received the lower end of the partition or cloth 11. The upper portion of one surface 21 is provided with a rib 22 adapted to engage and lock with an elongated recess 23 in the other surface, thus gripping the fabric of the partition 11 when the spout sections are held together. The sections on their exterior surface, as shown, are gradually tapered. They are held together by a screw threaded ring 24 which is

slipped on from the lower end and tightens the

sections together. A similar screw threaded ring or collar 25 engages the lower set of threads 18 and is adapted in the usual manner, to receive and hold in position a nozzle 26 on the very lower end of the spout sections, and this nozzle may have any suitable shape of opening through which the frosting or confectioner's material is to be discharged.

One of the surfaces 14 of one of the spout sections is provided preferably with an integral, dependent, tapered blade 21, extending down from the lower edge of the surface 14 and into the nozzle to act as a partition in the nozzle between the material coming from one spout section and the material coming from the other. Therefore, 15 these materials do not come into contact until just before they emerge from the nozzle 26.

In the operation of the device and assuming the bag has been already formed and provided with the sewn intermediate partition 11, the nozzle 20 sections are inserted in the top of the bag and moved down to the bottom assuming the position shown in Figure 2, at which time, the tapered form of the bag will snugly receive the sections at the lower end thereof, and the rib 22 and recess 23 at the upper spaced adjacent surfaces of the sections will grip the bag partition or intermediate wall 11 tightly. The tongue 16 will be lying in the aperture 15. The collar 24 is then screwed into place to tighten the sections 30 together and then the nozzle 26 is placed on the lower end of the spout and the collar or ring 25 is screwed in position to hold this nozzle in place. The confectioner will then manipulate the bag in the usual manner to squeeze the material from the compartments. The partition 11 shown in Figure 2, is shown as a common wall between the two compartments, but it is clear that when two separate bags are used, this wall 11 will be formed of two layers of material forming adjacent sides of the two bags, the lower ends of which are connected to the respective spout sections. When separate bags are used, they can be manipulated separately to dispense material from one or the other whereas in the specific preferred form shown, the dispensing is of two kinds of material simultaneously. By having nozzle members of different shapes and with different shapes of openings at the bottom thereof, the character of the cross section of issuing material can be changed at will.

This device is simple and efficient, and enables one device to perform several functions in connection with decorating cakes and similar articles; it can be taken apart quickly and easily to be cleaned, and as quickly and easily reassembled.

While the invention has been described in detail and with respect to the preferred form shown in the drawings, it is not to be limited to such details and forms since many changes and modifications may be made in the invention without departing from the spirit and scope of the invention in its broadest aspects. Hence, it is intended to cover any and all forms and modifications of the invention which may come within the language or scope of any one or more of the appended claims.

What I claim as my invention, is:

1. In combination, a dispensing bag having a partition dividing the bag into separate compartments, said compartments being of smaller cross section at the bottom than at the top thereof, sectional spout portions of the same general shape as said compartments, each compartment adapted to receive a spout portion, said portions

resting in said compartments to form a complete spout, means for holding the spout sections together, and cooperating means on the spout sections to grip the lower end of the partition therebetween to form a plurality of continuous passages through the bag and the spout section for the material to be dispensed.

2. In combination, a dispensing bag having a partition dividing the bag into separate compartments, said compartments being of smaller cross section at the bottom than at the top thereof, sectional spout portions of the same general shape as said compartments, each compartment adapted to receive a spout portion, said portions resting in said compartments to form a complete spout, means for holding the spout sections together, and cooperating means on the spout sections to grip the lower end of the partition therebetween to form a plurality of continuous passages through the bag and the spout section for the material to be dispensed, a nozzle member added to fit over the lower ends of the spout sections, collar means to hold the nozzle member in position, and a blade on the lower end of one of said spout sections and extending into the nozzle member to a point near the lower end thereof to separate the material flowing from the spout sections.

3. In combination, a tapered dispensing bag having a central fabric partition extending downwardly therein to form a pair of downwardly tapered compartments, a pair of downwardly tapered symmetrical spout sections, each section disposed in a compartment in side by side relation with respect to each other, said compartments having openings in the bottoms thereof through which said sections project, said sections having flat abutting lower surfaces, means thereon to interlock said surfaces and align said sections, the upper surfaces of said sections being displaced to form a narrow passage to receive the lower end of said bag partition, tongue and groove elements on said displaced surfaces to engage said partition therebetween, the periphery of said sections being threaded and a threaded ring collar adapted to be screwed into place to hold the sections together, a nozzle member to be placed against the lower ends of said sections, the lower ends of said sections being also threaded and a screw threaded ring collar adapted to be screwed on to the lower ends of said sections to hold and engage said nozzle to hold it in place, a tapered blade dependent from the lower end of one of the abutting surfaces of said spout sections, said blade extending down into the nozzle to separate the material passing through said compartments and said sections.

4. In a device of the character described, a dispensing bag having a partition dividing the bag into a pair of downwardly tapered compartments of semi-circular cross section, said compartments being open at the bottom, a pair of spout sections of the same general shape as said compartments, each section adapted to rest in a compartment so as to form a complete spout of circular cross section, each spout having a vertical face, one of said faces being apertured and the other having a tongue adapted to lie in said aperture when the sections are in said compartments, the outer surfaces of the sections having screw threads, and a collar adapted to be threadably engaged with said threads to hold the sections together.

5. A device of the character described in accordance with claim 4 wherein one of said faces

has a transverse rib element and the other face has a transverse groove adapted to coact with said rib element to grip the partition therebetween when the sections are in their respective compartments.

6. A device of the character described in accordance with claim 4 wherein the upper portions of said faces are offset to provide a space therebetween when the sections are in their respective compartments, a transverse rib on one of said offset portions and a transverse groove on the other offset portion, said groove and rib adapted to coact so as to grip the partition therebetween.
